UNITED STATES PATENT OFFICE.

HAROLD E. McCREARY, ALBERT E. JESSER, AND ALONZO B. MONTGOMERY, OF APOLLO, PENNSYLVANIA, ASSIGNEES TO APOLLO HOLDING CORPORATION, OF APOLLO, PENNSYLVANIA, A CORPORATION OF DELAWARE.

ROLL HEATER.

Application filed November 17, 1925. Serial No. 69,717.

This invention relates to roll heaters and more particularly to an apparatus adapted for heating rolls employed in rolling sheet metal and the like.

- 5 It has been found to be exceedingly difficult to properly heat the rolls employed in rolling sheet metal, the rolls usually being heated by passing therebetween highly heated sheets, the rolls becoming heated by 10 contact with the heated sheets. It has been found, however, that the rolls do not operate effectively unless properly heated and accordingly the sheets initially passed between the rolls to heat them are imperfect and must 15 be scrapped. Heating the rolls in this manner is very inefficient and costly due to the large number of sheets which it is necessary to pass between the rolls before they are sufficiently heated.
- 20 An important object of the present invention is to provide a heating apparatus adapted to substantially surround the rolls to impart heat thereto whereby cold rolls may be heated or the previously heated rolls 25 maintained in heated condition until it is desired to use them again.

A still further object is to provide an apparatus of the above mentioned character which is adapted to heat the rolls gradually 30 and evenly without causing undue expansion of the surface portions thereof, thus preventing the cracking of the rolls.

A still further object is to provide an apparatus of the above mentioned character 35 which is particularly adapted to employ gas burners for supplying heat to the rolls, and to provide means for effectively controlling the distribution of the heat to provide an efficient heating action.

40 A still further object is to provide an apparatus for heating rolls comprising a pair of complementary units adapted to fit around opposite sides of the roll whereby they may be easily placed in position and 45 removed by the use of overhead cranes or other lifting apparatus.

Other objects and advantages of the invention will become apparent during the course of the following description.

50 In the drawings, we have shown one embodiment of the invention. In this showing:

Figure 1 is a side elevation of the apparatus in operation,

Figure 2 is a section on line 2—2 of Figure 1,

Figure 3 is a fragmentary sectional view of one of the rolls and a portion of the heat control means,

Figure 4 is a detail sectional view through one of the end walls of the heating apparatus, portions of the heating distributing plates and associated elements being shown in elevation,

Figure 5 is a detail sectional view through a portion of the end walls, parts being shown in elevation,

Figure 6 is a detail view of the damper control means,

Figure 7 is a detail sectional view taken longitudinally through one of the heat distributing plates, and,

Figure 8 is a fragmentary sectional view on line 8—8 of Figure 1.

Referring to the drawings, the numerals 75 10 and 11 indicate upper and lower rolls adapted to be rotatably supported by trunnions 12 for rolling sheet metal in the usual manner. The trunnions are supported in the usual bearings (not shown).

The apparatus comprising the present invention includes a pair of complementary casing sections indicated as a whole by the numeral 13. Each of the sections 13 is provided with end walls 14 which have abutting edges 15. The end walls extend throughout the height of the sections 13 and are adapted to be arranged close to the surface of the rollers as indicated in Figure 2, each of the end walls being provided 80 with arcuate cut out portions 16 arranged concentric with the upper and lower rolls.

The abutting edges 15 of the end walls are inclined as shown in Figure 2 for a purpose to be described. Each section 13 is provided at its upper portion with arcuate walls 17 preferably arranged concentric with the upper roll and spaced a substantial distance therefrom. The arcuate portions 17 terminate in outwardly inclined walls 18, as 85 shown in Figure 2, and the walls 18 are connected at their lower ends to horizontal inwardly extending walls 19. The walls 18

may be provided with suitable hooks 20 secured thereto by rivets or the like 21 to facilitate placing the sections 13 in position and removing them. Below the horizontal walls 19, each section 13 is provided with a 90

substantially vertical wall 22 which extends outwardly near its lower end as at 23 and then downwardly, substantially vertically as at 24. The walls 18, 22 and 23 are preferably lined 5 with asbestos or similar material 25 to minimize the radiation of heat. The walls 19 and 24 are provided with air openings 26 for a purpose to be described. Above the wall 19, each wall 22 is provided with an 10 inwardly and upwardly extending wall 27, the inner end of which is turned as at 28 about a longitudinal rod 29 preferably extending between the end walls 14. The rods 29 act as bracing means between the end 15 walls, as will be apparent, and additional rods 30 are preferably connected between the end walls 14 where these walls extend inwardly between the rolls as shown in Figure 2. If desired, the walls 18 and 22 may 20 be provided with suitable apertures covered with glass 31 or other transparent material held in position by plates 32. These apertures are provided merely for the purpose of permitting the operator to observe conditions 25 within the heating apparatus, as will be apparent.

Below the wall 24, each of the casing sections is provided with a bottom wall 33, and the inner ends 34 of the bottom walls 30 are spaced apart a substantial distance, as clearly shown in Figure 2. The bottom walls 33 extend outwardly beyond the walls 24, as shown at 35. Heating chambers 36 are arranged beneath each of the walls 33, as shown in Figures 1 and 3, these heating chambers extending transversely of the apparatus. Any number of the heating chambers 36 may be employed, but in the present instance we have illustrated two of these 40 chambers beneath each of the bottom walls 33, and the chambers beneath each wall are preferably arranged in end to end relation with respect to the chambers beneath the other bottom wall. Each of the heating 45 chambers 36 includes an outer wall 37 and an inner wall 38, the walls 38 being arranged against each other, as shown. The walls 38 extend upwardly beyond the walls 33, to a point near the lower roll and each 50 wall 38 is provided with an outwardly extending horizontal portion 39. Each heating chamber is further provided with a bottom wall 40 and side walls 41, and the side walls are provided with openings 42 for a 55 purpose to be described.

Means are provided for securing the upper ends of the casing sections together when the device is in operation. One arcuate wall 17 is provided near its top and 60 near the ends thereof with an upwardly extending lug 43 which is adapted to be arranged in an opening in a locking plate 44 secured at its opposite end to the arcuate wall 17 of the other casing section. Intermediate the plates 44 the adjacent edges of

the walls 17 are spaced apart as shown in Figure 2 to provide a flue for the passage of products of combustion from the burners to be described.

In sheet rolling mills gas is usually 70 available and accordingly we prefer to employ gas burners as the means for supplying heat to the rolls. As shown in Figure 2, burner tubes 45 are arranged respectively above each wall 19 inwardly of each wall 75 24, and within each of the burner chambers 36. The burners are provided with burner openings 46 and the burners within the chambers 36 may be provided with spreaders 47 arranged thereover.

Gas may be supplied from any suitable source of supply to a supply pipe 48 shown in Figure 1. This pipe may be connected to a thermostatically controlled valve 49 of any suitable type and thermostats 50 are 85 adapted to control the valve 49. It will be obvious that a separate pipe 48 and valve 49 is employed for each of the casing sections, and each of the pipes 48 may be connected to the gas main by a suitable flexible hose. The thermostats 50 are preferably arranged inwardly of the walls 22 just below the walls 27 as shown in Figure 2. From each valve 49 the gas is supplied to a depending pipe 52 which is connected at its lower end to a horizontally extending pipe 53. From the pipe 53 of each casing section, gas may be supplied to the burners within the chambers 36 through vertical pipes 54 provided with valves 55. Gas to the other burners may be supplied through pipes 56 which also may be provided with manually controlled valves 57. It will be noted that each of the burner tubes is arranged adjacent the air openings 90 26 and 42 to be supplied with auxiliary air therefrom to properly support combustion.

Means are provided for regulating the heat supplied to the lower roll 11. A plurality of heat directing plates 58 are arranged around the lower half of the lower roll as shown in Figure 2. Each of the plates 58 is connected at one end to a longitudinal rod 59 which extends through the end walls 14. From the rods 59 each plate extends upwardly and outwardly and has its outer end turned about a rod 60. Each rod 60 extends a slight distance beyond the end of the plate by which it is carried and has its inner end turned backwardly upon the plate as shown at 61 to space the end of the plate from the next adjacent plate. Thus it will be apparent that spaces are provided between the adjacent plates 58. The ends of the plates which carry the rod 60 obviously are not positively supported and accordingly are free to move, the plates being pivotally supported by the rods 59. In order to maintain the plates in proper position, we provide a pair of chains 62 100 105 110 115 120 125 130 135

each of which is secured at its lower end to one of the horizontal flanges 39. The upper ends of the chains are secured to longitudinal rods 63 which pass through the 5 end walls 14 of the casing sections and are pivotally supported thereby. One end of the rod 63 is provided outwardly of the casing with an operating handle 64 contacting with a quadrant 65 having apertures 66 10 therein. The operating handle 64 is arranged outwardly of the quadrant and is provided with a bolt 67 having a rounded inner head adapted to frictionally engage selected openings 66 to maintain the shaft 15 63 in any desired position. Each shaft 63 is provided with a damper comprising a pair of plates 68 each of which is turned about the shaft 63 as at 69. The inner ends of the damper plates are spaced apart to 20 permit the upper ends of the chains to be wound about the shafts 63 in a manner to be described.

The operation of the apparatus is as follows:

25 The casing section on the right in Figure 2 is first lowered in position by an overhead crane or any suitable means, whereupon the usual casing section is brought into position. With the casing section to the left 30 in Figure 2 swinging from the hooks 20, it will be apparent that the upper end of the casing will swing inwardly and the lower end outwardly. The casing is lowered until the apertures in the plates 44 engage the 35 lugs 43, whereupon the casing is lowered until it assumes the position shown. Conversely, when it is desired to remove the apparatus, the section to the left is first lifted to release the plates 44 from the lugs 43, 40 and due to the inclination of the abutting edges 15 of the end walls, the section first raised may be readily removed from position. The other section then is removed by lifting the hooks 20 by a crane or other 45 means.

It will be apparent that the apparatus is adapted to heat cold rolls to the proper temperature, but may be employed just as efficiently for maintaining previously used rolls 50 in heated condition until they are to be used again. With the burners in operation, the heat generated will affect the thermostats 55 which in turn are adapted to control the valves 49 to regulate the amount of gas supplied to the burners. The manually controlled valves associated with each burner may be operated to control the proportion of gas supplied to each burner as experience 60 may show to be desirable. The products of combustion from the burners 45 in the chambers 36 pass upwardly between the ends of the bottom plates 33 and pass upwardly 65 around the rollers. Owing to the position of the inner ends of the bottom plates 33 it will be apparent that the products of com-

bustion from the chamber 36 will be directed toward the bottom of the lower roll and will pass around the roll tending to maintain close contact therewith, this contact however, being prevented by the plates 58. It 70 will be apparent therefore, that the highly heated gases are prevented from playing directly against the surface of the roll to cause undue expansion of the surface thereof. It has been found that introducing 75 highly heated gases against the surface of a roll will cause rapid expansion thereof which in turn sometimes causes large pieces of the roll to crack. The products of combustion 45 inwardly of the walls 24 tend to 80 rise vertically within the walls 22, mingling with the gases from the lower burners when they approach the dampers 68. Some of the gases will pass outwardly of the chamber plates, but these members tend to retard the 85 upward flow of the gases to force some of them through the spaces between the adjacent ends of the plates 58 whereby some of the gases will flow around the lower roll in contact therewith. The gases from the burners 45 above the walls 19 mingle with the 90 gases from the other burners after they have passed around the lower roll to cause efficient heating of the upper roll. It will be apparent that the addition of the asbestos or 95 similar material 25 prevents excess radiation of heat from the casing.

The free ends of the plates 58 are adapted to be supported by the chains 62 as previously described, and the upper ends of these 100 chains are secured to the shafts 63. If it is found that insufficient heat is being delivered to the lower roll, the shafts 63 may be turned by the operating handle 64 to partially close the space between the plates 68 105 and the side walls 22. This obviously will retard upward movement of the gases from the lower portion of the casing thus causing an increased flow of the gases between the plates 58 and increasing the heat delivered to the lower roll, the plates 58 being 110 separated as the damper plates are closed. The products of combustion pass outwardly from the casing through the space between the upper ends of the arcuate casing 115 walls 17.

The openings 26 in the walls 19 and 24 are adapted to supply auxiliary air to support combustion of the gases as will be apparent. The spreaders 47 are adapted to 120 spread the gases toward opposite sides of the chambers 36 where they mingle with the air passing through the openings 42 to properly complete combustion. The conditions within the casing may be determined through 125 the windows 31 while the apparatus is in operation.

It is to be understood that the form of our invention herewith shown and described is to be taken as a preferred example of the 130

same and that various changes in the shape, size and arrangement of parts may be resorted to without departing from the spirit of the invention or the scope of the subjoined claims.

We claim:

1. A roll heater comprising a casing adapted to surround a pair of adjacent rolls, said casing having substantially closed side walls, and end walls shaped to substantially fit said rolls, heating means arranged in said casing, and adjustable means for directing heat within said casing from said heating means.

15 2. A roll heater comprising a casing adapted to surround a pair of adjacent rolls, said casing having substantially closed side walls, and end walls adapted to substantially fit said rolls, burners arranged in said casing, and adjustable means for controlling the direction of movement of some of the products of combustion from said burners.

25 3. A roll heater comprising a casing adapted to surround a pair of adjacent rolls, said casing having substantially closed side walls, and end walls shaped to substantially fit the sides of said rolls, a plurality of burners arranged in said casing, said burners including a lower burner arranged near the bottom of said casing, and adjustable means for directing at least a portion of the products of combustion from said lower burner toward one of said rolls.

35 4. A device constructed in accordance with claim 3 provided with manually controlled means for supplying fuel to said burners, and thermostatic means controlling the total amount of fuel supplied to said burners.

40 5. A roll heater comprising a casing adapted to surround a pair of adjacent upper and lower rolls, said casing including substantially closed side walls, and end walls shaped to substantially fit the sides of said rolls, said casing being provided adjacent its upper end with a flue, a heater arranged in each side of said casing intermediate the top and bottom thereof, a lower heater adapted to heat the lower portion of said casing, and adjustable means for controlling distribution of heat from said lower heater.

55 6. A device constructed in accordance with claim 5 wherein said adjustable means includes a plurality of movable plates arranged adjacent a portion of said lower roll.

7. A device constructed in accordance with claim 5 wherein said adjustable means includes a series of movable plates surrounding the lower portion of said lower roll, the upper ends of said series of plates being spaced from the side walls of said casing, and dampers arranged between the upper ends of said series of plates and the side walls of said casing.

65 8. A roll heater comprising a casing

adapted to surround a pair of adjacent upper and lower rolls, said casing including substantially closed side walls, and end walls shaped to fit the sides of said rolls, said casing being provided adjacent its upper end 70 with a flue, means for heating the interior of said casing intermediate the top and bottom thereof on opposite sides of said rolls, lower heating means for heating the interior of the lower portion of said casing, and a 75 series of adjacent plates surrounding the lower portion of said lower roll, said plates having their adjacent edges relatively movable toward and away from each other.

9. A device constructed in accordance 80 with claim 8 provided with means for adjusting said plates.

10. A device constructed in accordance with claim 8 wherein the upper ends of said series of plates are spaced from the side 85 walls of said casing, means for adjusting said plates, and dampers arranged between the side walls of said casing and the upper ends of said series of plates.

11. A device constructed in accordance with claim 8 wherein the upper ends of said series of plates are spaced from the side walls of said casing, dampers arranged between the side walls of said casing and the upper 90 ends of said series of plates, and means for simultaneously operating said dampers and said plates to move said dampers toward closed positions as the spaces between the adjacent edges of said plates increase.

12. A roll heater comprising a casing 100 adapted to surround a pair of adjacent upper and lower rolls, said casing including substantially closed side walls, and end walls shaped to fit the sides of said rolls, said casing being provided adjacent its upper end with a flue, means for heating the interior of said casing intermediate the top and bottom thereof on opposite sides of said rolls, lower heating means for heating the interior 105 of the lower portion of said casing, a series of horizontally arranged plates surrounding the lower portion of said lower roll, each of said plates being pivotally connected at one horizontal edge to said casing, the opposite edge of each plate being free and arranged slightly outwardly of the pivoted edge of the next adjacent plate, and means for controlling movement of the free edges of said plates.

13. A device constructed in accordance 110 with claim 12 wherein said last named means comprises a flexible member passed around said plates and contacting with the free edges thereof.

14. A device constructed in accordance 115 with claim 12 wherein said last named means comprises a pair of flexible members each having one end fixed outwardly of said plates and substantially beneath the center 120 of said lower roll, said flexible members con-

tacting with the free edges of said plates, and means for vertically adjusting the free ends of said flexible members.

15. A device constructed in accordance with claim 12 wherein said last named means comprises a pair of flexible members each having one end fixed outwardly of said plates beneath the center of said lower roll, said flexible members contacting with the free edges of said plates, and a pair of rotatable shafts arranged in said casing on opposite sides of said lower roll, the opposite ends of said flexible members being secured to said shaft.
16. A roll heater comprising a casing adapted to surround a pair of adjacent upper and lower rolls, said casing including substantially closed side walls, and end walls shaped to fit the sides of said rolls, said casing being provided adjacent its upper end with a flue, burners arranged in the lower portion of said casing, a series of horizontally arranged plates surrounding the lower portion of said lower roll, each of said plates being pivotally connected at one horizontal
- edge to said casing, the opposite edge of each plate being free and arranged slightly outwardly of the pivoted edge of the next adjacent plate, a pair of flexible members each having one end fixed outwardly of said plates beneath the center of said lower roll, said flexible members contacting with the free edges of said plates, the upper ends of said series of plates being spaced from the side walls of said casing, a shaft arranged adjacent each upper end of said series of plates, the opposite ends of said flexible members being secured to said shaft to be wound thereon, and dampers secured to said shafts.
17. A device constructed in accordance with claim 16 provided with a pair of heating chambers arranged beneath said casing and communicating therewith, said burners being arranged in said chambers.

In testimony whereof we affix our signatures.

HAROLD E. McCRERY.

ALBERT E. JESSER.

ALONZO B. MONTGOMERY.
